SMOKING PIPE BOWL INSERT OR SIMILAR ARTICLE

Friedrich Arthur Dewes, New York, N. Y.

Application October 5, 1954, Serial No. 32,549

Term of patent 7 years

(Cl. D85—8)

To all whom it may concern:

Be it known that I, Friedrich Arthur Dewes, a citizen of the United States of America, residing in New York city, county of New York, and State of New York, have invented a new, original, and ornamental Design for a Smoking Pipe Bowl Insert or Similar Article, of which the following is a specification, reference being had to the accompanying drawing, forming part thereof, wherein,

Figure 1 is a front perspective view of a smoking pipe bowl insert or similar article showing my new design.

I claim:

The ornamental design for a smoking pipe bowl insert or similar article, substantially as shown.
